STARTING AND OPERATING CIRCUIT FOR ELECTRIC DISCHARGE DEVICES

Eugene Lemmers, Cleveland Heights, Ohio, as-
signor to General Electric Company, a corpora-
tion of New York

Application November 28, 1945, Serial No. 631,381

3 Claims. (Cl. 315—254)

1

My invention relates generally to gaseous electric discharge devices, and more particularly to starting and operating circuits therefor.

An object of my invention is to provide circuits for starting gaseous electric discharge devices, particularly lamps, such as the known commercially available fluorescent lamps, by means of which the lamps will be started practically instantaneously and will operate with comparatively low power consumption in the ballast. Another object is to provide such an arrangement in which supplementary means are provided to heat the electrodes during starting, and then the supplementary heating means is reduced or neutralized when the lamp starts, without the use of moving parts such as switches.

In one type of circuit now in wide use with fluorescent lamps, the lamp is connected across a source of power in series with a reactor or choke coil, and the activated filamentary electrodes of the lamp are temporarily short-circuited by a suitable switch to connect them in series across the power source and thereby cause them to be preheated to an electron emitting temperature. Upon opening the switch, an inductive kick or surge from the choke coil effects starting of a discharge in the lamp. Such circuits provide reliable starting, operate at good efficiencies, and make for long life of the lamp electrodes. However, disadvantages are the need for a switch which must be carefully designed and must be replaced periodically, and the relatively slow starting occasioned by the preheating period.

In another type of circuit arrangement, referred to as the so-called "instant start" type, switches are dispensed with and the lamp started by connecting it across the terminals of a transformer capable of supplying a potential sufficiently high to break down the gaseous column between the electrodes and start a discharge therebetween. However, since the lamp operates at a voltage much lower than that necessary to start it, the transformer unavoidably operates with a relatively high power loss. The starting without pre-heating of the activated electrodes is also hard on the electrodes.

According to the present invention, an arrangement is provided having advantages of both types of arrangements referred to above, but eliminating the disadvantages. Thus, the lamps start substantially instantaneously without undue sputtering of the electrodes and with relatively low power loss in the ballast.

Further features and advantages of my invention will appear from the following description of species thereof.

Fig. 1 is a diagrammatic view of an electric discharge device and a starting and operating circuit therefor incorporating my invention.

Fig. 2 illustrates the invention in a two-lamp circuit.

Figs. 3 to 6 illustrate modifications of the starting arrangement of Figs. 1 and 2.

2

Referring to Fig. 1, the discharge device 1 shown therein may be an ordinary fluorescent lamp or the positive column electric discharge type comprising a tubular envelope 2 with thermionic electrodes 3 and 4, preferably in the form of a coiled coil of tungsten wire activated with the usual mixture of barium and strontium oxides. If desired, the electrodes 3, 4 may be proportioned so that the voltage drop across each of them with a current sufficient to bring it to electron-emitting temperature is slightly greater than the resonance or ionization voltage of the gas or vapor in the lamp, whereby a local arc discharge is formed across the ends of the electrode. The envelope of the lamp contains a gas, such as argon, at a pressure of a few millimeters and a small quantity of mercury which, during operation of the lamp, has a low pressure of the order of ten microns, and the side walls of the envelope have a phosphor coating thereon which when excited by a discharge through the mercury vapor produces fluorescence.

The lamp is connected across a suitable source of potential, preferably a voltage step-up auto transformer 5, and in series with a current limiting inductance or choke coil 6. The auto transformer in turn is connected across a source of power 7 which, for example, may be a 115 volt, 60 cycle supply.

In accordance with my invention, I provide windings 8 and 9 on the core of the auto transformer 5 and inductively coupled therewith, and I also provide windings 10 and 11 on the core of the choke coil 6 and inductively coupled therewith. The filamentary electrodes, in this case, are each connected in series with a winding of the supply transformer and a winding of the choke coil. Thus electrode 3 is connected in series with inductively coupled auto transformer coil 8 and in series with inductively coupled choke coil 11. However, the coils 8 and 11 are connected in opposite electromotive force to each other, i. e., in "bucking" relationship. Filamentary electrode 4 connected in series with coils 9 and 10 and filamentary electrode 3 connected in series with coils 8 and 11 comprise the starting and electrode heating circuits 12 and 13, respectively.

It is preferable to connect the inductively coupled transformer coils 8 and 9 in such a manner that their voltages are in phase with and add to the voltage across the auto transformer 5.

When the power supply is turned on, coils 8 and 9 inductively coupled to the auto transformer 5 are energized and thus cathode heat, enough for electron emission, and potential for starting is supplied to filamentary electrodes 3 and 4. As soon as the discharge occurs between the filamentary electrodes 3 and 4 and current flows through the choke coil 6 the E. M. F. of the coils supplying cathode heat, namely 8 and 9, is opposed by the induced E. M. F. or bucking effect in coil 10 and 11 respectively. The cathode heat

power is thus automatically turned off. Perfect opposition between the coils is not necessary for the successful operation of the circuit. In fact, a small amount of additional cathode heat is sometimes desirable during operation of the arc discharge to lower cathode potential drop.

The presence of electrode heating windings 8 and 9 makes it possible to use a transformer 5 having a lower open circuit voltage than would otherwise be necessary to start the lamp 1. However, those windings would entail a power consumption which is not necessary during operation of the lamp since the electrodes are then kept heated by the discharge. Such power consumption is eliminated by the bucking windings 10 and 11.

It is possible that the heating of one of the electrodes may be dispensed with. In that event, one heating winding and its cooperating bucking winding may be eliminated. Thus, for instance, the windings 8 and 11 may be omitted. In that event, the electrode 3 may be short-circuited, if desired, by connecting its terminals or leads together outside the lamp.

Fig. 2 incorporates Fig. 1 in a two-lamp circuit. The lead circuit, at the left, embodies corresponding parts of the lag circuit except for the addition of the capacitor 14. The corresponding parts of the lead circuit are designated with the same numbers primed.

Fig. 3 incorporates the same above-described corresponding parts of Fig. 1 and Fig. 2 for the lead circuit but embodies voltage step-down transformers 15 and 16 to which are inductively coupled the coils 19' and 11', and coils 8' and 9' respectively. This arrangement reduces the wave distortion due primarily to the capacitor 14 and the combination of the choke 6' and autotransformer 5 usually sharing some iron in their magnetic circuits. During operation of the lamp, the primary of transformer 16 draws very little current.

The arrangement of the step-down transformer 16 as shown in Fig. 3 may be used in those cases where the lamp 1' has a break down voltage lower than the voltage of the line or power source 7, in which case the step-up transformer 5 is eliminated.

Fig. 4 incorporates the same above described corresponding parts of Fig. 1 except that in the filament heating circuit 13 a section 18 of the choke coil 6 is used as a bucking winding instead of the coil 11 of Fig. 1. Also, a section 17 of the transformer 5 is used as the heating winding in heating circuit 12 instead of the winding 9 of Fig. 1. In other words, the windings 17 and 18 are in this case directly coupled to the transformer 5 and choke coil 6, instead of being inductively coupled as are the windings 9 and 11 in Fig. 1.

The circuit of Fig. 5 is similar to that of Fig. 2 except that the bucking effect for the heating circuit of a given lamp is obtained from the operating circuit of the other lamp. Thus, in the heating circuits 12 and 13 for lamp 1, the heating windings 9 and 8 are connected to the bucking windings 11' and 10', respectively, which are coupled to the choke coil 6' in the operating circuit of the lamp 1'. Similarly, the heating windings 8' and 9' for lamp 1' are connected to bucking coils 10 and 11 which are coupled to the choke coil 6 in the operating circuit of lamp 1. This arrangement can result in still lower wattage loss per lamp than the Fig. 2 arrangement.

Fig. 6 incorporates the same above described

corresponding parts of Fig. 1 except that coils 8 and 11 are connected in parallel with each other and with filamentary electrode 3, and coils 9 and 10 are also connected in parallel with each other and with filamentary electrode 4, thus comprising heating circuits 13 and 12 respectively.

What I claim as new and desire to secure by Letters Patent of the United States is:

1. In combination, a source of current, a gaseous electric discharge device having at least one thermionic electrode and a cooperating electrode, an autotransformer, an inductive ballast, a voltage step-down transformer inductively isolated from said autotransformer and said ballast and comprising a primary winding connected in series relation with said discharge device, said ballast and said autotransformer, and an electrode heating winding inductively coupled to said source to supply heating current to said thermionic electrode, the secondary winding of said step-down transformer being connected to oppose the flow of current in said heating winding upon flow of current through said primary winding of said step-down transformer.

2. In combination, a source of current, a gaseous electric discharge device having at least one thermionic electrode and a cooperating electrode, an autotransformer energized from said source and a voltage step-down transformer having a primary winding connected in series relation with an inductive ballast and said autotransformer, a capacitance connected in series relation with the last-mentioned elements, and an electrode heating winding inductively coupled with said source and connected to supply heating current to said thermionic electrode, the secondary of said step-down transformer being connected to oppose the flow of current through the primary winding of said step-down transformer upon the flow of current through said device.

3. In combination, a source of current, and a gaseous electric discharge lamp having at least one filamentary electrode and a cooperating electrode, an autotransformer energized from said source and an inductive ballast connected in series relation therewith, means for supplying heating current to said filamentary electrode comprising a winding inductively coupled to said source, a capacitance connected in series relation with said autotransformer and said ballast, and means for reducing the flow of current to said filamentary electrode upon the flow of current between said electrodes without distorting the wave form of the voltage supplied to said device and comprising a voltage step-down transformer having a primary winding connected in series relation with said discharge device and a secondary winding connected in opposition to said heating winding.

EUGENE LEMMERS.
